UNITED STATES PATENT OFFICE.

SOLOMON GILBERT TOUCHSTONE, OF COLUMBIA, SOUTH CAROLINA.

TENSION FEELER.

Application filed September 27, 1923, Serial No. 665,079. Renewed October 25, 1924.

To all whom it may concern:

Be it known that I, SOLOMON G. TOUCHSTONE, a citizen of the United States, residing at Columbia, in the county of Richland 5 and State of South Carolina, have invented a new and useful Tension Feeler, of which the following is a specification.

This invention relates to a tension feeler, which is adapted to be used in connection 10 with slubbers, intermediates, speeders, or roving machines and the like.

In the operation of this class of machine, it sometimes happens that the contact gears or changing device get out of order, or 15 through atmospheric changes, or through the tampering with the tensioning device by unskilled help, the ends or sliver become tighter than desired, resulting in uneven or weak roving, thereby causing uneven or 20 weak yarn to be produced.

The principal object of the present invention is to provide means whereby this undesirable result is prevented, and in the specific form herein disclosed the invention 25 includes means which automatically shifts the shipper rod whenever the tension becomes tight, and stops and locks the machine, so that it is impossible to operate the same until it has been properly adjusted.

30 The structure of the invention, and the operation thereof, in connection with textile machinery will be more particularly described in connection with the accompanying drawings, which illustrate the invention 35 in its preferred form.

In the drawings:

Figure 1 is a longitudinal section through the rear part of a roving machine, showing the third samson in elevation.

40 Figure 2 is a perspective view of the feeler device.

Figure 3 is a rear elevation of the machine.

Figure 4 is a plan view thereof.

45 Figure 5 is a front elevation of the machine in operative position.

Figure 6 is a similar view, with parts locked in inoperative position.

50 Figure 7 is a detail view of the latch and locking mechanism.

Figure 8 is a detail view of the feeler support.

For the sake of illustrating the application of the invention to the textile art, I 55 have shown in connection therewith a portion of a roving machine of common con-

struction, the roll beam of which is indicated by the numeral 10, and the second and third samsons by the numerals 11 and 12, respectively. Top and bottom cones 13 and 14 are carried by shafts 15 and 16 suitably journaled in the frame of the machine, and are connected by a belt 17. This belt is embraced by a fork 18 carried by the end of the longitudinally travelling rack 19, so that as the rack is reciprocated, the belt is caused to travel longitudinally of the cones to vary the speed of the spindle. The cone 13 is driven by any suitable means, as by the gearing 20, while the shaft 16 is rocked 70 in the usual manner by the gearing 21. Pinions 22 secured to the shaft 16 mesh with vertical lifter racks 23 to reciprocate vertically the frame 24, which carries the bolster rail. These racks 23 are suitably mounted in guides formed in the samsons, as indicated at 25, Figure 1, and the frame 24 is counterbalanced by weights 26 attached to chains 27, which pass over sheaves 28 journaled on the samsons, and are secured at their opposite ends, as indicated at 29.

A shipper rod 30, Figures 3, 4 and 6, is mounted to slide in one or more guides 31 secured to the frame of the machine, and is 85 adapted to be moved longitudinally to throw the machine into or out of operation. Secured to the rod 30 is a stop or tappet 32 adapted to be engaged by the upwardly extending arm of a swing lever 33, which is 90 fulcrumed on a stud 34 projecting from a bracket 35, which is secured to the beam 10. The lever has a laterally extending arm 36 to which is adjustably secured a weight 37, which is sufficient to swing the lever 33 and 95 the shipper rod 30 longitudinally, and render the machine inoperative. The lever, however, is normally held with the arm 36 raised by means of a latch 38 pivoted to the lower end of the lever, and having a notched 100 end 39 adapted to project through and engage a stop plate 40 secured to the samson 12. A tappet or knock-off 41 is, however, secured to the rack bar 19, and when the rack bar reaches the end of its movement, 105 engages the inclined portion 42 of the latch and raises the same to permit the arm 36 of the lever to swing downwardly, and to effect an automatic stopping of the machine.

Means are also provided to shift the shipper rod in case the frame 24 passes beyond its proper limit of movement for any reason.

To this end a vertical knock-off rod 43 is slidably mounted on bearings 44 on the samson 12, and is provided with an adjustable finger 45 disposed so as to be engageable by 5 a lifter catch or finger 46 secured to the lower end of the rack bar 23, when the latter reaches the upward end of its movement. This raises the rod 43, which has secured to its upper end a bunter 47 adapted to engage 10 the end of the latch bar 38, and release the same from the plate 40. The rod 43 also carries two spaced lugs 48, between which projects a dog 49 pivoted at 50 on the samson and bearing a weight 51 on the opposite 15 side of its pivot, so as to support the rod 43 as the frame 24 descends.

In the type of machine herein described, the shaft 15 is customarily provided with a bevelled gear 52 meshing with a bevelled 20 skip gear 53 carried at the upper end of a vertical contact shaft 54, which is journaled in brackets 55 secured to the samson 11, and is adapted to operate the reversing gear. This shaft 54 carries contact dogs 56, which 25 engage the builder 57 as the frame is raised or lowered. The builder shaft 58 is rotated step by step by the gearing 59. A pinion 60 secured to the shaft 54, meshes 30 with a gear 61 on a vertical stud shaft 62 carried by an arm 63, which is fulcrumed on the shaft 54, and the stud shaft carries at its upper end a contact gear 64, which is adapted to mesh with one of the change gears 65. The change gears are carried by a sleeve 68, 35 which is keyed to a shaft 66 having a pinion 67 operatively connected with the rack bar 19. The sleeve 68 may be moved longitudinally on the shaft 66 to adjust the change gears through the medium of a manually 40 operated pinion 69 in mesh with annular teeth 70 on the shaft. The gears 65 may be counterbalanced by a weight 71. The shaft 61 may be provided with a hand wheel 74, or other suitable means, for returning the 45 cone rack bar to its initial position.

In the normal operation of the machine, the latch 38 is raised to disengage the notched end 39 from the plate 40 by the knock-off 41, so that the shipper rod is shifted only when the cone rack bar 19 reaches the end of its movement.

By means of my invention, however, means are provided for releasing the latch to permit the movement of the shipper rod whenever the tension of the sliver becomes greater than that for which the machine is set, thereby making further operation of the machine impossible until the tension is adjusted, and consequently making it impossible 55 to produce an inferior, uneven yarn.

In carrying out my invention, I provide a 60 feeler bar 75, which is supported transversely of the machine, and over which the sliver 76 is drawn in its passage from the rollers 77 to the nose of the flier. The feeler

bar 75 is supported at the end of an angular rod 78, which is supported at its other end by being screwed into a bearing 79, journaled on a stud 80, projecting laterally from a bracket 81 secured to the roll beam 10. 70 Screwed into the opposite side of the bearing 79 is the upper end of a rod 82, the lower end of which is turned laterally, as at 83, and provided with a loop 84. This loop receives the upper end of a trigger 85 intermediate pivoted, as at 86, to the dog 49, and having a downwardly projecting sharpened end 87 adapted under certain conditions to engage the notch 88 formed on the upper side of the lifting finger 46. chine, and see that the sliver is at the proper tension, before the operation can be resumed.

While I have shown and described the invention as applied to a specific type of machine, it will be understood that this is merely for the purpose of illustration, and that the same is adapted to be applied to any similar machine used in the textile art. It will also be understood that the invention 10 is not necessarily limited to the precise structure shown and described, but that modifications may be made with respect to size, shape and other details of the device without departing from the salient features 15 of the invention as expressed in the appended claims.

What is claimed is:

1. In a machine of the class described, the combination of a shipper rod, an arm 20 movable to shift the same, a latch normally holding said arm against movement, means normally in contact with the sliver, and operable by abnormal tension thereof to release said latch.

2. In a machine of the class described, a stationary frame, a vertical reciprocating frame mounted thereon, a shipper rod, an arm movable to shift the same, a latch normally holding said arm against movement, 30 a feeler pivotally supported on the stationary frame and normally in contact with the sliver, a trigger movable by the feeler into the path of movement of said reciprocating frame when the sliver is under abnormal 35 tension, and means operable by said trigger when raised by the reciprocating frame to release said latch.

3. In a machine of the class described, the combination of a longitudinally movable shipper rod, an arm movable to shift the same, a latch normally holding said arm against movement, means normally in contact with the sliver and operable by abnormal tension thereof to release said latch, 45 to permit the shifting of the shipper rod, and means for automatically locking said mechanism after said rod is shifted to prevent starting the machine again until it has been adjusted.

4. In a machine of the class described, the combination of a stationary frame, a bolster rail frame mounted for vertical reciprocation thereon, a shipper rod mounted for longitudinal movement on the stationary 55 frame, an arm movable to shift said shipper rod, a latch normally holding said arm against movement, a feeler bar pivotally supported on the stationary frame and normally in contact with the sliver, a trigger 60 movable by the feeler into the path of movement of said reciprocating frame when the sliver is under abnormal tension, means operable by the trigger to release the latch upon the first upward movement of the reciprocating frame after the trigger has been

rocked, whereby to permit the shifting of the shipper rod, and means for automatically locking said mechanism after the shipper rod is shifted to prevent starting the machine again until it has been adjusted. 70

5. In a machine of the class described, the combination of a shipper rod, a latch controlling the same, a vertically movable knock-off rod, a weighted dog normally supporting the rod in contact with the latch, 75 and means normally in contact with the sliver and operable by abnormal tension thereof to raise the knock-off rod and thereby release the latch to permit the shipper rod to be shifted.

6. In a machine of the class described, the combination of a stationary frame, a vertically reciprocable frame mounted thereon, a knock-off rod carried by the stationary frame, a counterbalanced feeler bar pivotally 85 supported on the stationary frame in contact with the sliver, a pivoted trigger rockable, by the movement of the feeler bar, into the path of a portion of the reciprocatory frame so as to be raised by the first upward movement thereof, and means operated by the upward movement of the trigger to actuate the knock-off rod. 90

7. In a machine of the class described, the combination of a stationary frame, a bolster rail frame reciprocably mounted thereon, a feeler bar rod intermediately pivoted on the stationary frame, a feeler bar carried by one end of the rod and normally in contact with the sliver, a knock-off rod carried by the 100 stationary frame, a pivoted dog normally supporting the knock-off rod, a trigger intermediately pivoted to the dog with its upper end in the path of the feeler bar rod, whereby an abnormal pressure on the feeler bar 105 rocks the trigger, and a finger projecting laterally from the reciprocatory frame and engageable with the lower end of the trigger when the latter is rocked, so as to raise said trigger upon the next upward movement of 110 the reciprocatory frame and actuate the knock-off rod.

8. In a machine of the class described, the combination of a stationary frame, a vertically reciprocable frame mounted thereon, 115 a knock-off rod carried by the stationary frame, a counterbalanced feeler bar pivotally supported on the stationary frame and normally in contact with the sliver, a pivoted trigger reciprocable by the movement of the 120 feeler bar, a finger projecting laterally from the reciprocatory frame and having a recess for receiving the lower end of the trigger upon the first upward movement of said frame after the trigger has been rocked, so 125 as to actuate the knock-off rod.

9. In a machine of the class described, the combination of a stationary frame, a vertically reciprocatory frame, a shipper rod, a latch controlling the same and having a 130

notch normally engaged with a part of the stationary frame, a knock-off rod carried by the stationary frame, means normally in contact with the sliver and operable by ab-
5 normal tension thereof to raise said knock-off rod and thereby raise the latch and release the shipper rod, and an upwardly projecting lug on the knock-off rod engageable with the notch in the latch to lock the shipper
10 rod after it has been shifted.

10. In a machine of the class described, the combination of a stationary frame, a vertically reciprocatory frame mounted thereon, a shipper rod, a latch controlling the same
15 and having a notch normally engaged with a part of the stationary frame, a knock-off rod carried by the stationary frame, a coun-

terbalanced feeler bar pivotally supported on the stationary frame in contact with the sliver, a pivoted trigger rockable, by the movement of the feeler bar, into the path of a portion of the reciprocatory frame so as to be raised by the first upward movement thereof, means operated by the upward movement of the trigger to raise the knock-off rod and thereby raise the latch and release the shipper rod, and an upwardly projecting lug on the knock-off rod engageable with the notch in the latch to lock the shipper rod after it has been shifted.

In testimony that I claim the foregoing as my own, I have hereto affixed my signature.

SOLOMON GILBERT TOUCHSTONE.
